UNITED STATES PATENT OFFICE

169,367

BOX

Frank Ferraro, Baltimore, Md.

Application July 21, 1952, Serial No. 20,695

Term of patent 3½ years

(Cl. D58—6)

To all whom it may concern:

Be it known that I, Frank Ferraro, residing at Baltimore, in the State of Maryland, have invented a new, original, and ornamental Design for a Box, of which the following is a specification, reference being had to the accompanying drawing, forming a part hereof.

Figure 1 is a top plan view of a box, showing my new design;

Figure 2 is a side view thereof; and

Figure 3 is a rear view thereof.

Figure 4 is a perspective view of the box in open position.

I claim:

The ornamental design for a box, as shown.
FRANK FERRARO.
